UNITED STATES PATENT OFFICE.

FERDINAND SCHWEDTMANN, OF ST. LOUIS, MISSOURI.

RADIATOR.

SPECIFICATION forming part of Letters Patent No. 658,928, dated October 2, 1900.

Application filed February 27, 1899. Serial No. 706,992. (No model.)

To all whom it may concern:

Be it known that I, FERDINAND SCHWEDTMANN, a citizen of the United States of America, residing at St. Louis, in the State of Missouri, have invented a certain new and useful Radiator, of which the following is such a full, clear, and exact description as will enable any one skilled in the art to which it appertains to make and use the same, reference 10 being had to the accompanying drawings, forming part of this specification.

The object of my invention is to construct a radiator for steam or hot water in which the radiating portions are made of sheet metal, such as thin wrought-iron, and to provide 15 means for connecting the several sections of the radiator together as effectively as can be done with the ordinary cast-iron radiator.

My invention consists in various novel features and details of construction, all of which are described in the following specification and pointed out in the claims affixed hereto.

In the accompanying drawings, which illustrate a two-column radiator made in accordance with my invention, Figure 1 is a side elevation. Fig. 2 is an enlarged section on the line 2 2 of Fig. 1. Fig. 3 is a view, also on an enlarged scale, similar to Fig. 2, but showing a slight modification. Fig. 4 is a section, 25 also on an enlarged scale, on the line 4 4 of Fig. 1, but showing the section in an uncompleted state. Fig. 5 is an enlarged section on the line 5 5 of Fig. 1, showing two sections joined together. Fig. 6 is a side elevation 30 showing the lower portion of one of the leg or end sections, and Fig. 7 is a section on the line 7 7 of Fig. 6.

Like marks of reference refer to similar parts in the several views of the drawings.

Each section of the radiator consists of a radiating portion and base, the former of 40 which is formed of two parts 10 and 11, stamped out of sheet metal, preferably thin wrought-iron. In order to secure the parts 10 and 11 together, I form on the edges of the part 10 a flange 12 and on the edges of the part 11 a flange 13, preferably of greater width than flange 12, which is bent around and firmly pressed against the sides of the 45 flange 12. Between the flanges 12 and 13 may be placed cement or other suitable substance

to render the joints steam or water tight. In the forms shown in Figs. 1 and 2 the metal is cut away between the two columns or radiating portions of the section, leaving an opening 14; but in place of this the metal of the parts 10 and 11 may be allowed to form a web 55 15 between the two columns, as shown in Fig. 3. In this case it will only be necessary to secure the two parts of the web together by rivets 16, as any slight leakage which may take place between the two columns will not in any way affect the efficiency of the radiator. In place of the method of joining the parts 10 and 11 shown in Figs. 2 and 3 the 60 flanges 12 and 13 may be made of the same width as shown in Fig. 4 and either secured together by rivets 17, brazed, or secured together in any other suitable manner.

At the lower end of the parts 10 and 11 70 bosses 20 may be formed and in the center of each of these bosses an indentation 21, as shown in Fig. 4.

22 is a cylindrical block which is preferably formed of cast-iron, but may be made of any 75 othersuitable unyielding material. Through the cylinder 22 is a longitudinal opening 23, which preferably has its central portion enlarged at 24 and is provided with lateral openings 25, communicating with the radiating 80 portions. The block 22 is placed between the parts 10 and 11, when they are to be secured together, with its ends projecting into the bosses 20, as shown in Fig. 4, and forms, with 85 said bosses, an unyielding connecting portion. Holes are then punched in the bosses 20 at the point indicated by the indentations 21, and the flanges thus formed are expanded into the longitudinal openings 23, as shown in Fig. 5, by means of a suitable tool, such as is used 90 by boiler-makers for expanding the tubes of boilers. A perfectly-tight joint can thus be formed between the interior face of the cylinder 22 and the metal of the bosses 20. The several sections of the radiator can now be 95 placed side by side, as shown in Fig. 5, and secured together by means of couplings 26, fitting into the longitudinal openings 23 in the usual manner.

I do not wish to limit myself to the exact 100 construction shown, as the sections may be provided with any desired number of columns

or flues, and other means may be provided for securing the sections together without departing from my invention.

I prefer to fill the lower ends of the sections 5 up to the lower edge of the lowest lateral opening 25 with cement 27, so as to prevent the accumulation of water in the lower ends of the sections. It is usual to provide the end sections with legs 28. These may either be 10 formed integral with the sections, as shown in Figs. 6 and 7, or they may be secured to the sections in any suitable manner.

It will be seen that the several sections of 15 my radiator are secured together as effectively as can be done with the ordinary cast-iron radiator. By the use of sheet metal a radiator to withstand the same pressure as a cast-iron radiator can be made very much lighter, or by making the sheet-metal radiator 20 of the same weight as a cast-iron one it will withstand a much greater pressure. A great saving in the cost of manufacture is also accomplished, as there is no loss in making the sheet-metal section, while in casting a large 25 percentage of the sections are lost, owing to defects in the castings. Any suitable ornamentation can be stamped upon the metal of the section at the same time that the general form is given to the metal.

30 Having fully described my invention, what I claim as new, and desire to secure by Letters Patent of the United States, is—

1. In a radiator for steam or hot water, a plurality of sections each consisting of a 35 wrought-metal radiating portion and a base, the base having a longitudinal opening and

openings communicating with the radiating portion, and the sides of the radiating portion being provided with openings and with flanges surrounding the same, said flanges being 40 adapted to be forced into the longitudinal opening of the base, in combination with means for clamping the flanges of the radiating portion against the inner periphery of the base. 45

2. In a radiator for steam or hot water, a plurality of sections each consisting of a wrought-metal radiating portion and base, the base having a longitudinal opening and openings communicating with the radiating portion and the sides of the radiating portion being forced around the ends and into the longitudinal openings of the base, in combination with a coupling fitting the longitudinal openings of two adjoining sections. 50

3. In a steam-radiator, a plurality of sections each having one or more columns or flues formed of sheet metal, hollow blocks of unyielding material carried by said sections and forming steam-tight joints with the metal 60 thereof, a filling of suitable material in the bottom of said sections to prevent the accumulation of water therein, and means for connecting said sections through said blocks. 55

In testimony whereof I have hereunto set 65 my hand and affixed my seal in the presence of the two subscribing witnesses.

FERDINAND SCHWEDTMANN. [L.S.]
